PORTRABLE DOUGH CUTTER

Roberto Meli, Bergamo, Italy

Application December 1, 1955, Serial No. 39,116

Term of patent 3½ years

(Cl. D55—1)

FIG. 1

FIG. 3

Fig. 1 is a front elevation of a portable dough cutter embodying my new design;

Fig. 2 is a side elevation taken from the left of Fig. 1; and

Fig. 3 is a side elevation taken from the right of Fig. 1.

I claim:

The ornamental design for a portable dough cutter, as shown.
